US0D1046823S

(12) **United States Design Patent** (10) **Patent No.:** **US D1,046,823 S**
(45) **Date of Patent:** **** Oct. 15, 2024**

(54) **EARPHONE**

(71) Applicant: **SHENZHEN FENDA SMART TECHNOLOGY LIMITED**, Shenzhen (CN)

(72) Inventor: **Yulin Chen**, Shenzhen (CN)

(73) Assignee: **SHENZHEN FENDA SMART TECHNOLOGY LIMITED**, Shenzhen (CN)

(**) Term: **15 Years**

(21) Appl. No.: **29/871,018**

(22) Filed: **Feb. 10, 2023**

(30) **Foreign Application Priority Data**

Aug. 12, 2022 (CN) 202230526751.2
(51) **LOC (14) Cl.** **14-01**

(57) **CLAIM**

The ornamental design for an earphone, as shown and described.

DESCRIPTION

FIG. 1 is a front, right and top perspective view of an earphone, showing my new design;
FIG. 2 is a rear, left and bottom perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof; and,
FIG. 9 is an enlarged view of portion of FIG. 2 thereof.
The broken lines shown in the drawings illustrate portions of the earphone that form no part of the claimed design.

1 Claim, 9 Drawing Sheets
